[57] CLAIM

The ornamental design for an animal feeder, as shown and described.

DESCRIPTION

FIG. 1 is a perspective view taken from the bottom front and right side of an animal feeder showing my new design;

FIG. 2 is a front elevational view thereof;

FIG. 3 is a right side elevational view thereof;

FIG. 4 is a top plan view thereof;

FIG. 5 is a rear elevational view thereof;

FIG. 6 is a left side elevation view thereof; and

FIG. 7 is a bottom plan view thereof.
